(57) **CLAIM**

The ornamental design for the shaving razor, as shown and described.

DESCRIPTION

FIG. 1 is a top perspective view of the shaving razor, showing the new design;

FIG. 2 is a front view of the shaving razor;

FIG. 3 is a rear view of the shaving razor;

FIG. 4 is a side view of the shaving razor;

FIG. 5 is a top view of the shaving razor;

FIG. 6 is a bottom view of the shaving razor; and,

FIG. 7 is a bottom perspective view of the shaving razor, showing the new design.

The broken lines illustrate portions of the safety razor and form no part of the claimed design.

1 Claim, 5 Drawing Sheets
